FISHING TACKLE BOX

Gary Wallazy, 14860 Lyons, Livonia, Mich. 48154

Filed Jan. 16, 1970, Ser. No. 20,951

Term of patent 14 years

Int. Cl. D3—99

U.S. Cl. D87—1

Fig. 2

Fig. 4

Fig. 1

Fig. 3

FIG. 1 is a front elevational view of a fishing tackle box showing my new design;

FIG. 2 is a front perspective view thereof, the two outside pull-out drawers, the inside pull-out drawer, and the slotted shelves being extended and the vertically sliding door being raised and fragmentarily shown for convenience of illustration;

FIG. 3 is a rear elevational view thereof; and

FIG. 4 is a rear perspective view thereof, the pull-out shelves being extended and the vertically sliding door being raised and fragmentarily shown for convenience of illustration.

I claim:

The ornamental design for a fishing tackle box, as shown and described.
